 Michigan Products Corporation, Michigan City,
 Ind., a corporation of Indiana

Application May 22, 1944, Serial No. 536,801

20 Claims. (Cl. 230—209)

The invention relates to centrifugal fans or blowers for heat treating furnaces and the like, and has for its principal object to provide a simple construction that will allow appropriate freedom of movement among the parts in expanding and in contracting while maintaining the necessary relationship in the whole for dynamic balance in use. Generally speaking, this is accomplished by making the blades carry the shrouds interlocked with their side edges for functional operation together but with freedom of relative movement in expanding and contracting and making the inner end portions of the blades fast to their hub or to their shaft for driving and to prevent outward bodily movement under centrifugal force.

Two double inlet fans and two single inlet fans are shown in the accompanying drawings. Figs. 1 to 8, and the corresponding description are taken from my application, Serial No. 450,847, filed July 14, 1942, of which the present application is a continuation in part. The remaining figures, Nos. 9 to 22, and the corresponding description disclose the preferred construction embodying improvements made in the course of further research and experience with the earlier construction in actual service.

In the accompanying drawings:

Figs. 1 and 2 are diagrammatic views of a double inlet fan and its associated parts in one form of installation;

Fig. 3 is a longitudinal sectional view through a fan and hollow fan shaft taken on the line 3—3 of Fig. 2;

Fig. 4 is a perspective view of one of the hub portions for securing the blades together and to the shaft, as shown in Fig. 3;

Fig. 5 is a section taken on the line 5—5 of Fig. 3, with parts of one of the shrouds and some of the blades broken away to reveal the construction and assembly;

Fig. 6 is a perspective view of one of the blades;

Fig. 7 is a section similar to Fig. 3, of a single inlet fan;

Fig. 8 is a perspective view of one of the blades of a single inlet fan;

Fig. 9 is a longitudinal sectional view through a fan and hollow shaft of the preferred construction and corresponding to Fig. 3;

Fig. 10 is a perspective view of one of the hub portions for securing the blades together and to the shaft, as shown in Fig. 9;

Fig. 11 is a part side elevation and part section taken on the line 11—11 of Fig. 9;

Fig. 12 is a perspective view of one of the blades in the preferred form of construction;

Fig. 13 is a fragment of one of the shrouds;

Fig. 14 is a sectional view corresponding to Fig. 9, of a single inlet fan of the preferred construction;

Fig. 15 is a perspective view of one of the blades of a single inlet fan shown in Fig. 14;

Fig. 16 is a fragment of the shroud at the left in Fig. 14;

Fig. 17 is a fragment of the shroud at the right in Fig. 14;

Figs. 18 and 19 are fragmentary sectional views corresponding to a portion of Figs. 9 and 14, and showing a different means of positively fastening the blades to the hubs or interlocking them with the hubs;

Fig. 20 is a fragment of a blade corresponding to Figs. 18 and 19;

Fig. 21 is a fragmentary view corresponding to Figs. 18 and 19, showing a further modified form; and

Fig. 22 is a fragment of a blade corresponding to that modified form.

But these particular forms and the corresponding description are used for the purpose of disclosure only and are not intended to impose unnecessary limitations on the claims.

In Figs. 1 and 2, 10 indicates a conventional form of masonry installation for a fan or blower within which is the metal casing 11 for a double inlet fan 12 mounted on a hollow water-cooled shaft 13, journaled in bearings 14 and driven by a motor 15 through V-belt drive 16. The inlet side of a water-cooling unit is shown generally at 17, and the return side is shown generally at 18.

Water cooling is ordinarily used in fan constructions for propelling high temperature fluids such as the gases circulated in heat treating furnaces.

The detail of the double inlet fan is shown in Figs. 3, 4, 5 and 6, Sheets 2 and 3. The fan is composed of twelve blades 19, two circular shrouds 20, and two hub portions 21, assembled on the hollow shaft 13.

From the perspective view in Fig. 6 it will be seen that the fan blades in this instance are each composed of a generally rectangular flat plate having the inner corners cut away at 22 and the inner end is integral with a sector shaped base 23, the assembled inner surfaces 24 of which conform to the cylindrical surface of the shaft 13. Adjacent to its base 23 each blade is thickened to form the filler pieces or machining pads 25.

At or adjacent to each edge, each blade is

thickened and provided with grooves 26 whereby at each side of each groove there appear ribs 27 and 28.

Each shroud 20 is a flat ring provided with outwardly opening slots 29, twelve in number, to receive the side edges of the several blades as the adjacent portions of the shrouds are received between the ribs 27 and 28.

Each hub portion 21 has an enlargement 30, the bore 31 of which is tapered to correspond with the tapered ends 32 of the bases 23. In this instance the taper is at an angle of 5°. The enlarged portions 30 are provided with slots 33 (Fig. 4) to receive the thickened portions 25 of the blades by means of which jaws 34 are formed on the enlarged portions 30, which straddle the corresponding blades.

The left hub 21 rests against a shoulder 35 (Fig. 3) on the shaft 13, and a key 36 in aligned keyways in the shaft and the hub portion effects the driving connection between them.

The right hub portion 21 (Fig. 3) and the shaft 13 are given a driving connection by a gib key 37 in aligned keyways in the hub portion and the shaft; and having a head 38 fitted against the right end of the hub portion. The key is inserted by a lengthwise movement to the left in Fig. 3, and made fast by a filler plate 39 secured to the shaft by screws 40.

Two additional gib keys 41, at 120° on centers from the key 38, are fitted in keyways 42 in the shaft and made fast by screws 43, each having a head 44 fitted tightly against the right end of the hub portion 21, as shown in Fig. 3.

There is a clearance at 45 (Fig. 5) between the adjacent blade bases 23 of not more than .005" with the result that when the hub portions and blades have been assembled, as shown in Fig. 3, the bases of the blades are clamped tightly against the cylindrical surface of the shaft 13.

There is a clearance of less than .002" between the side faces of the jaws 34 and the thickened portions 25 of the blades. There is a clearance of about .003" between the ribs 27 and 28 and the adjacent portions of the shrouds, and a clearance of about .010" at the bottom of the notches 29 in the shrouds. These clearances are suitable for a fan of 18" in diameter and are given to insure that the disclosure is complete, but not with the intent of imposing corresponding limitations on the claims.

According to one mode of assembly, the left hub portion 21, with its key 36, is emplaced upon the shaft 13, as shown in Fig. 3. The blades are inserted in the slots of the shrouds and the sub-assembly brought to approximately the position shown in Fig. 3. The right hub portion 21 is then forced home and made fast by the keys 37 and 41.

The form of single inlet fan shown in Figs. 7 and 8 (Sheet 4) corresponds in every particular except that the blades are like the left half of the blades in Fig. 6 and the right shroud closes the entire face of the fan, leaving a single inlet opening at the left. Hence, in view of the detailed description that has been given with respect to the double inlet fan construction, it will be sufficient to add the corresponding reference numerals to Figs. 7 and 8 to avoid repetition.

According to the preferred procedure, the hub portions and blades will be cast and the shrouds will be made from sheets. By weighting the blades and a slight amount of fitting, the assembly can readily be given dynamic balance, and the construction described will insure that the

blades are held in proper relation with respect to the shaft, both for driving and to prevent outward movement due to centrifugal force, and the shrouds will be maintained in proper relation to the blades while each blade and shroud will be free for relative movement in expanding and contracting.

For fans to be used in temperatures up to about 1600° F. an alloy of iron containing about 25% of chromium and about 12% of nickel has been found satisfactory, but sometimes the composition will have to be changed to meet particular conditions. It may be necessary to use an alloy that is inherently weaker in order to get greater resistance to corrosion or abrasion. For temperatures up to 900° F. steel may be used.

After the parts have been finished they should be annealed at temperatures above the highest to be expected in service, in order to remove any internal strains that might be released in service and throw the fan out of dynamic balance.

Fans made substantially as above described and as illustrated in Figs. 1 to 8 have been in actual service for a sufficient period to demonstrate their great practical utility in high temperature furnaces, including those having especially corrosive and abrasive atmosphere. Experience with these fans, and they have been followed carefully, and further research directed particularly to service in furnaces at temperatures from 1500° F. to well above 1650° F., have resulted in further improvements which make the fans still more valuable under extreme conditions. These improvements now represent the preferred construction.

The detail of the preferred form of double inlet fan is shown in Figs. 9-13 (Sheets 5 and 6). The fan is composed of twelve blades, generally indicated by 50, two circular shrouds 51, and two hub portions 52, assembled on a hollow shaft 53.

From Figs. 9 and 12, it will be seen that each blade is composed of a generally flat plate having an inner portion 54 provided with outwardly converging side edges 55, by virtue of which it becomes somewhat wedge shaped. Each edge 55 is provided with flanges or machining pads 56, which join sector shaped flanges 57, the twelve of which form a circular arch, as shown in Fig. 11, between the hub portions 52, as shown in Fig. 9. Each sector shaped flange 57 is provided with an opening 58 aligned with an opening 59 in the adjacent flange 60 on the hub portion 52, and these aligned openings receive fastening dowel pins 61, twenty-four of which positively fasten and hold the blades against outward movement under centrifugal force. These pins, being arranged on a circle, conform to the dynamic balance necessary in the fan.

The main body of the inner portion 54 of each blade is thickened relative to the outer portion 62, the inner portion being on the order of $\frac{3}{8}$ " thick, and the outer portion is $\frac{1}{4}$ " thick. The change in thickness is made very gradual to avoid any abruptness, and avoiding abruptness is a rule throughout this fan construction; and, while no distinct line can be indicated for the change from one thickness to the other, the thinner portion is roughly bounded by the line 63 in Figs. 9 and 12.

The machining pads 56 and the sector shaped flanges 57 are joined to the inner portions 54 by gently curving fillets 64, generally indicated by the shading. In order to provide metal and strength about the inner ends of the openings 58, bosses 65 are provided adjacent to the sector

shaped flanges 57, and they are joined to the thinner inner portions 54 by other gently curving fillets 66. The extreme inner edges 61 of the blades are comparatively straight, and together the twelve form a sort of polygon around the shaft 53, but spaced from it. The flanges 57 are slightly longer than the intervening portions 54.

At or adjacent to each side edge, each blade is thickened and provided with grooves 68, whereby at each side of each groove there appears ribs 69 and 70, the ribs 70 being relatively short and the ribs 69 relatively long. The latter are approximately as long as the shrouds are wide, and the former are only about the depth of the slots in the shrouds.

Each shroud 51 is a ring provided with outwardly opening slots 71, twelve in number, to receive the side edges of the several blades as the adjacent portions of the shrouds are received between the ribs 69 and 70. The shrouds are of uniform thickness to about the depth of the slots 71, and from there inwardly they are gradually thickened, as indicated at 72, to provide additional strength for resisting the bursting tendencies of centrifugal force on the shroud as a whole.

The flange 60 of each hub portion has an inner flat face 73 for contact with and bearing against the grouped faces 57 of the blades. Outwardly of this face 73, which is at right angles to the axis, each flange 60 has an inclined face 74 provided with twelve slots 75 to receive and hold the machined faces 56 of the converging edges 55 of the inner portion 54 of the blades. While the slots are backed by a considerable thickness of flange metal, the inner portions are rounded at the corners 76 to avoid any abrupt change of surface that might foster cracks. The fit between the sides of the slots and the machined faces 56 is close and, together with the dowel pins 61, provides a strong driving and holding joint between the hubs and the blades. The adjacent surfaces being remote from the axis of rotation, minor accumulations of tolerances have less effect on the fit than with the construction shown in Figs. 3 and 6.

Each hub portion 52 has a bore 77 to receive the shaft 53, to which it is keyed. The left hub portion 52 in Fig. 9 rests against the shoulder 78 on the shaft, and the right hub portion in Fig. 9 is held against the blades by a large locking collar 79, made fast by a lock nut 80 and a lock washer 81, having one tab 82 fitting in one of the key slots in the shaft 53, and other tabs 83 and 84 bent into the respective notches 85 and 86 in the lock nut 80 and the locking collar 79.

The fan shaft is water cooled and is made of carbon steel. The hubs 52 are of some suitable alloy. The shaft and the hubs, therefore, have different coefficients of expansion. The tendency thus created to increase the clearance between the hub portions and the shaft as the fan is heated up is greatly augmented by the fact that the shaft is water cooled and the hubs are not. Bearing in mind that all of the fan is carried by the hubs on the shaft and that a 30 inch fan wheel substantially as shown in Figs. 9-13 will weigh on the order of 650 pounds, it is apparent that a slight eccentricity between the hub portions and the shaft results in enormous forces due to lack of dynamic balance.

To prevent this condition and to obtain and maintain dynamic balance, three or more keys or splines are used to effect a driving connection between the shaft and the hub portions.

In Figs. 9, 10, and 11, keys are shown, and they will probably be most used, and preferably the keyways and keys will be machined to give contact at the side faces only, the outer faces radially being free. In this instance, three keys arranged at 120° on centers are shown as the simplest form. Four keys arranged at 90° on centers, etc., are contemplated. Three keys is the smallest number that will fairly insure and maintain dynamic balance.

Integral keys or splines will be preferred by some to separate keys fitted in aligned keyways in the hub portions and shaft, and preferably the integral splines will be in one piece with the hub portions and broached with great accuracy to fit the keyways in the shaft.

The locking collar, lock washer, and lock nut for making the hub members 52 fast on the shaft have a great advantage over the gib keys shown in Figs. 3 and 7, in providing greater strength due to the extended surface contact and also because the locking collars can be adjusted to allow for the necessary expansion which may be calculated accurately within reasonable limits.

As heretofore made in a 30-inch fan, the outer portions of the shrouds were .245 inch thick with an allowance of plus or minus .003, and the grooves 68 were .250 inch with an allowance of plus .003 minus .000. The inner edges of the shrouds were $\frac{1}{2}$ inch thick, and the corners were rounded on a $\frac{1}{4}$ inch radius.

The slots 75 in the flanges 60 of the hub portions were $\frac{1}{2}$ inch wide plus .005 minus .000, and the inclined edges 55 at the machined faces 56 were .498 inch thick plus .002 minus 0.000. The sector shaped flanges 57 were 23° 26'. The openings 58 were 1 inch in diameter reamed plus .000 minus .002. The openings 59 in the flange 60 were the same, and all the openings were arranged on circles of an 8 inch diameter. The machined faces 56 extended to approximately 8 $\frac{1}{2}$ inches from the axis of rotation and were about $\frac{1}{2}$ inch wide. The side faces of the sector shaped flanges 57 were about $\frac{3}{4}$ of an inch wide.

The outer surface of the flange 60 on the hub portion was about 70° 28' inclined to the vertical, and the inner face of the same flange was about 60° to the vertical. The inside diameter of the shrouds was 20 inches. There was thus provided ample inlet openings at each side somewhat in excess of the discharge opening at the perimeter of the fan.

The slots 71 in the shrouds were $1\frac{1}{8}$ inches deep, or about $\frac{1}{3}$ of the 5 inch radial width of the shrouds.

Adjacent sector shaped flanges 57 are spaced by an angle 6° 34'.

These and other clearances and dimensions are given to insure complete disclosure for one size of fan that has been satisfactory in actual service, but they are not intended to impose any limitations on the claims.

According to one mode of assembly, the inner hub portion is in place on the shaft against the shoulder 78. The blades are assembled with the two shrouds and brought into position with the pins projecting from the hub flange 60 into the openings in the blades. The other hub flange is then brought into place; the collar 79 is threaded on, the lock washer slipped into place, the lock nut screwed up, and the tabs 83 and 84 bent over.

The single inlet fan embodying the charac-

teristics of the double inlet fan shown in Figs. 9-13 is shown in Figs. 14-17 (Sheet 7). It corresponds to the double inlet fan in every particular, except that the blades are cut away at the right, as shown best by comparing Figs. 9 and 14, and the shroud 151 at the right is wide enough to close the right side of the fan, leaving the entire inlet at the left. Hence, in view of the detailed description that has been given with respect to the double inlet fan, it will be sufficient to add the corresponding numerals to Figs. 14-17.

Instead of using the dowel pin 61 (shown in Figs. 9-14), some will prefer to fasten the blades 50 to the hub portions 52 by rings 86, as shown in Fig. 18, fitted into circular grooves 87 in the hub flanges 60 and circular notches 88 in the blades as shown in Fig. 20. By this construction, of course it will be necessary to set the blades in a fixture for machining the notches 88 accurately, but the assembly is somewhat simplified.

A further alternative is shown in Fig. 19, where, instead of a separate ring 86 shown in Fig. 18, the hub flange 60 is provided with an integral ring flange 89. A reverse of that will be preferred by some, and is shown in Figs. 21 and 22, where the blades are provided with circular ribs 90 fitting in a circular groove 91 in the hub flange 60.

According to the preferred construction, the hub portions, the blades, and the shrouds are cast from a suitable alloy and machined to make all the blades, the two shrouds, and the two hub portions, respectively, identical. After the machining, the parts should be annealed at a temperature above the highest to be expected in service in order to remove internal strains that might be released in service and throw the fan out of balance. By weighing the blades and a slight amount of fitting, the assembly can be readily given dynamic balance and the construction described will insure the maintenance of that balance in service as well as the necessary strength for a long period of service.

The purpose of the pins or rings for fastening the blades to the hubs is to make them secure, each at the same distance from the axis of rotation; in other words, to establish a datum line at which each of the blades is fastened and held against outward individual movement due to centrifugal force.

The purpose of making the inner portions of the blades wedge shaped and the hubs to correspond is to give the hubs a grip on the blades to a great distance from the axis of rotation as an element of safety against a blade, or a portion of a blade, getting free on account of a break across between two of the fastening pins or rings.

The slots in the hubs to receive the inner portions of the blades present a much easier machining job than in the early construction, for the angle between two adjacent radii effects a considerable divergence in spacing at the rim of the hubs or adjacent to the rim of the hubs. Hence, a machining tolerance in that area corresponding to the tolerance in the early construction will give a great deal closer fit and a more effective drive between the hubs and the blades.

The inclination of the hub flanges provides the necessary inlet or intake, and in the improved construction the intake on the two sides between the hub flanges and the shrouds gives an intake area in excess of the discharge at the perimeter of the fan.

Each slot 71 in the shrouds 72 is $\frac{3}{8}$ of an inch wide, and the bottom is formed by a $\frac{3}{8}$ inch drill before the slotting. It is $1\frac{1}{8}$ inches deep, and receives the corresponding portion of the blade between the ribs 69 and 70, where it is $1\frac{1}{2}$ inches wide. This portion is also $\frac{3}{8}$ of an inch thick, only unavoidable manufacturing clearance being allowed.

Bearing in mind that the machined faces 56 on the inner portions of the blades are firmly and accurately held in place in the slots 75 of the hub flanges 60 to a diameter of 15 inches in a 30 inch fan, it will be apparent that the shrouds are borne upon and driven by 12 blades accurately positioned in the open ended slots 71. Being thus borne and driven without any actual attachment to the blades, they are not only free to expand and contract independently of the blades but in effect they float in rotation subject only to centrifugal force.

According to one scheme of design, the resultant of one-half the centrifugal force on each shroud should be assumed as applied to a radius at right angles to the diameter severing that half from the other, and hence one-half of that resultant force indicates the stress at each end of the said diameter. From this, it follows that the slots 71 should be made as shallow as practical under the conditions to avoid undue weakening of the shrouds at the slots, for when a fan is working under extreme temperatures, on the order of 1600° to 1800° Fahrenheit, some of the alloys used lose a great deal of the normal tensile strength, and there is likelihood that centrifugal force will cause a creep or elongation in line with the slots which would change the clearances and cause an actual enlargement of the diameter of the shroud. An empirical rule is that the slots should not be more than one-third of the radial width of the shroud, but they need not necessarily be as much as that.

It is fundamental that thickening the shroud throughout its radial dimension would not provide any greater strength, for the centrifugal force would increase in exact proportion to the thickening. Any increase might be had by thickening the inner portion—that is, the radially inner portion—of the shroud, and theoretically the strength could be most advantageously obtained by thickening at or adjacent to the inner periphery, but this would violate the cardinal principle that there should be no abrupt changes in section and no corners. Hence, the tapered design shown in Figs. 9, 13, and 16 providing the flat inner face of the shroud at right angles to the axis of rotation and the inclined outer face from adjacent to the bottom of the slots 71 to the inner perimeter. This outer face need not necessarily be a straight line, but may be curved.

The shroud 151 at the closed side of the single wheel in Fig. 14 needs no thickening for the additional strength is provided by the smaller opening in the shroud, resulting in the greater extent of metal radially.

The particular relation between the outer portions of the blades and the shrouds permits the element of freedom in expansion and contraction while providing ample support in driving. It also permits the blades to be made separate from the hubs, thereby avoiding the complications of casting, and by the scheme here disclosed the blades are secured to the hub portion and through the hub portion to the shaft in a way that not only fastens them with certainty against outward

movement under centrifugal force, but also holds them in the correct line with respect to the slots in the shrouds and preserves them from the slight malpositioning that might occur due to the accumulation of tolerances in a different construction. Of course, tolerances may accumulate in the structure shown, but they are very likely to be found by the assembly inspection, and corrected.

In connection with the construction shown in Figs. 3 to 8 inclusive, it has been found preferable to eliminate the taper in the bore 31 of the hub portions 21 and the corresponding taper 32 on the bases 23.

I claim:

1. In a centrifugal fan, a plurality of blades in circular arrangement about a common axis of rotation with their inner portions converging inwardly toward said axis and their outer portions diverging outwardly from said axis, a shaft, hub members grasping the blades by their inner end portions to bind them fast to the shaft, and shrouds carried by the blades, one at each side of the circular arrangement of blades, each shroud having outwardly opening slots in which grooved side edges of the blades are received with freedom of the blades and shrouds to have relative movement in expanding and contracting.

2. In a centrifugal fan, a plurality of blades in circular arrangement about a common axis of rotation with their inner portions converging inwardly toward said axis and their outer portions diverging outwardly from said axis, hub members grasping the blades by their inner end portions to hold the blades against individual bodily movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting.

3. In a centrifugal fan, a plurality of blades in circular arrangement about a common axis of rotation with their inner portions converging inwardly toward said axis and their outer portions diverging outwardly from said axis, means to hold the blades by their inner end portions against individual bodily movement outwardly due to centrifugal force, and shrouds carried by the blades, one at each side of the circular arrangement of blades, each shroud having outwardly opening slots in which grooved side edges of the blades are received with freedom of the blades and shrouds to have relative movement in expanding and contracting.

4. In a centrifugal fan, a plurality of blades in circular arrangement about a common axis of rotation with their inner portions converging inwardly toward said axis and their outer portions diverging outwardly from said axis, means to hold the blades by their inner end portions against individual bodily movement outwardly due to centrifugal force, and shrouds carried by the blades, one at each side of the circular arrangement of blades, each shroud having slots in which the side edges of the blades are engaged with freedom of the blades and shrouds to have relative movement in expanding and contracting, and each blade having a rib at each side edge overlapping the adjacent slot in the shroud for preventing relative axial movement of the blades and shrouds.

5. In a centrifugal fan, a plurality of blades

in circular arrangement about a common axis of rotation with their inner portions converging inwardly toward said axis and their outer portions diverging outwardly from said axis, means to hold the blades by their inner end portions against individual bodily movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting.

6. In a centrifugal fan, a plurality of blades in circular arrangement about a common axis of rotation with their inner portions converging inwardly toward said axis and their outer portions diverging outwardly from said axis, said inner portions being enlarged axially, a shaft, hub members securing said enlarged inner portions to the shaft, and annular shrouds each having an outwardly open slot for each blade interlocked with a groove in the adjacent blade whereby the shrouds are maintained connected to the blades and axial separation of the blades and shrouds is prevented by the interlocked grooves and slots.

7. In a centrifugal fan, a plurality of blades in circular arrangement about a common axis of rotation with their inner portions converging inwardly toward said axis and their outer portions diverging outwardly from said axis, said inner portions being enlarged axially, a shaft, hub members securing said enlarged inner portions to the shaft, and annular shrouds each having a slot for each blade open at the outer periphery of the shroud and terminating short of its inner periphery interlocked with a groove in the adjacent blade whereby the shrouds are maintained connected to the blades and mounted thereon.

8. In a centrifugal fan, a plurality of blades in circular arrangement about a common axis of rotation with their inner portions converging inwardly toward said axis and their outer portions diverging outwardly from said axis, said inner portions being enlarged axially, a shaft, hub members securing said enlarged inner portions to the shaft, each blade having at its side edges inner and outer ribs providing grooves between the ribs, and annular shrouds each having a slot for each blade receiving said grooves to interlock the shrouds with the blades and maintain the shrouds mounted on the blades.

9. In a centrifugal fan, a shaft, a plurality of generally radially extending blades mounted on the shaft and each having a side edge thickened and oppositely grooved, and an annular shroud having a slot for each adjacent pair of blade grooves open to the outer periphery of the shroud and terminating short of the inner periphery, each of said slots and the adjacent pair of grooves being interfitted to mount the shroud on the plurality of blades.

10. In a centrifugal fan, a shaft, a plurality of generally radially extending blades mounted on the shaft and each having its side edges thickened and oppositely grooved, and a pair of annular shrouds each having a slot for each adjacent pair of blade grooves open to the outer periphery of the shroud and terminating short of the inner periphery, each of said slots and the adjacent pair of grooves being interfitted to mount the pair of shrouds on the plurality of blades.

11. In a centrifugal fan, an annular shroud

having slots open at its outer periphery and extending toward but terminating short of its inner periphery, a plurality of blades each having a pair of oppositely facing grooves formed in a side edge whereby the blades may be assembled with the shroud by moving the blades inwardly of the shroud with each pair of grooves interfitted with one of the slots, and means for securing the inner ends of the blades about a common axis of rotation to hold the assembly of blades and shroud together.

12. In a centrifugal fan, a shaft, hub portions on the shaft, a plurality of blades in circular arrangement about said shaft with their outer portions diverging outwardly from the axis and their inner portions converging inwardly toward the axis and clamped between the said hub portions, and shrouds carried by the blades, one at each side of the circular arrangement of blades and interlocked with the several side edge portions of the blades by joints preventing axial separation of the blades and shrouds and providing clearance between the blades and shrouds for individual freedom of the blades and shrouds to have relative movement in expanding and contracting.

13. In a centrifugal fan, a shaft, a plurality of blades in circular arrangement about said shaft with their inner portions converging inwardly toward the shaft and their outer portions diverging outwardly away from the shaft, hub members sleeved over the shaft having flanges grasping said inner portions with clearance for expansion and contraction with respect to said inner portions, but holding them against radially outward movement under centrifugal force and against rotary movement relative to the shaft, and shrouds carried by the blades, one at each side of the circular arrangement of blades and interlocked with the several side edge portions of the blades by joints preventing axial separation of the blades and shrouds and providing clearance between the blades and shrouds for individual freedom of the blades and shrouds to have relative movement in expanding and contracting.

14. In a centrifugal fan, a plurality of blades in circular arrangement about a common axis of rotation with their inner portions converging inwardly toward said axis and their outer portions diverging outwardly from said axis, means to hold the blades by their inner portions against individual movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting, said shrouds being thickened toward the inner periphery.

15. In a centrifugal fan, a plurality of blades in circular arrangement about a common axis of rotation with their inner portions converging inwardly toward said axis and their outer portions diverging outwardly from said axis, means to hold the blades by their inner portions against individual movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting, said

shrouds being thickened gradually toward the inner periphery.

16. In a centrifugal fan, a plurality of blades in circular arrangement about a common axis of rotation with inner portions converging inwardly toward said axis and outer portions diverging outwardly away from said axis, said inner portions having inwardly diverging side edges forming axial enlargements, means interlocked with the inner portions of the blades at the same distance from the axis to hold them against individual bodily movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting.

17. In a centrifugal fan, a plurality of blades in circular arrangement about a common axis of rotation with inner portions converging inwardly toward said axis and outer portions diverging outwardly away from said axis, said inner portions having inwardly diverging side edges forming axial enlargements, inclined hub portions grasping the diverging side edges of the inner portions of the blades to hold them against individual bodily movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting.

18. In a centrifugal fan, a plurality of blades in circular arrangement about a common axis of rotation with inner portions converging inwardly toward said axis and outer portions diverging outwardly away from said axis, said inner portions having inwardly diverging side edges forming axial enlargements, inclined hub portions grasping the diverging side edges of the inner portions of the blades to hold them against individual bodily movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting, the inner peripheries of the shrouds being spaced from the adjacent hub portions sufficiently to provide an intake in excess of the peripheral discharge.

19. In a centrifugal fan, a plurality of blades in circular arrangement about a common axis of rotation with enlarged inner portions converging inwardly toward said axis and relatively wide outer portions diverging outwardly away from said axis, means to hold the blades by their enlarged inner portions against individual bodily movement outwardly due to centrifugal force, and shrouds carried by the blades, one at each side of the circular arrangement of blades and interlocked with the several side edges of the blades by joints preventing axial separation of the blades and shrouds and providing individual freedom of the blades and shrouds to have relative movement in expanding and contracting.

20. In a centrifugal fan, a plurality of blades

in circular arrangement about a common axis of rotation with enlarged inner portions converging inwardly toward said axis and relatively wide outer portions diverging outwardly away from said axis, hub members interlocked with the enlarged inner portions of the blades at a uniform distance from the axis of rotation to hold them against individual bodily movement outwardly under centrifugal force and against rotary move-

ment independent of the hub members, and shrouds carried by the blades, one at each side of the circular arrangement of the blades and interlocked with the several side edges of the blades by joints preventing axial separation of the blades and shrouds and providing individual freedom of the blades and shrouds to have relative movement in expanding and contracting.

CARL NYGREN.
